UNITED STATES PATENT OFFICE

1,996,713

LAMP

Chauncey E. Waltman, Chicago, Ill., assignor to
Sandel Manufacturing Co., Chicago, Ill., a corporation of Illinois

Application May 25, 1933, Serial No. 672,856

1 Claim. (Cl. 240—81)

This invention relates to improvements in floor lamps and more particularly to the type of floor lamp known in the trade as a "bridge lamp".

In lamps of the above character heretofore constructed, the switch employed for turning on and off the lamp is disposed within the socket and is actuated by means of a pull chain extending through said socket. The sockets generally provided for lamps of this character have some means associated therewith for the attachment of a suitable shade within which the light bulb is enclosed.

The provision of a circuit closing device in the socket, the actuation of which is through the pull chain, makes it somewhat inconvenient in attaching the shade, as well as having the effect of somewhat marring the appearance of the shade by reason of the pull chain extending over the same. Another disadvantage in the provision of a pull chain at that point is that the actuation of the same is somewhat interfered with by reason of the position of the shade and also the pull on the chain generally tends to displace the entire lamp, with the result that the same may be tipped or knocked over.

It is the main object of this invention to provide a switch for controlling the passage of electricity to the lamp which may be in the form of a rotatable switch, so disposed in the lamp as not to interfere with the attachment of the shade, nor will the shade interfere with the actuation of said device or with the attractive appearance of the lamp.

Another object of this invention is to provide in a lamp of the character described, a circuit closing device which will be disposed in the arm of the lamp removed from the socket within which the light bulb is mounted.

A further object of this invention is to provide in a lamp of the character described, a switch for controlling the passage of electricity to the light bulb, said switch being disposed at some point along the arm of the lamp removed from the socket and in position to form substantially an extension or a part of said arm.

A still further object of this invention is to provide in a lamp of the character described, having a transverse arm, upon one end of which is provided a lamp socket with means surrounding the same for receiving in threaded relation a lamp shade, of an improved switch for controlling the passage of electricity to said lamp, said switch being disposed along the arm and arranged so as to present the appearance of forming a part of said arm.

A still further object of this invention is to provide in a bridge lamp of the character described, having a transverse arm upon one end of which is provided a lamp socket and shade, of a switch for controlling the passage of electricity through said lamp, said switch being so arranged as to form a part of the arm or the lamp base whereby the general appearance of the lamp will not be marred by the presence of pull chains and the like.

A still further object of this invention is to provide in a lamp of the character described, a novel and improved arrangement for the switch for controlling the passage of electricity to the lamp, said arrangement making for a more simplified and economical construction and being otherwise efficient for carrying out the purposes for which it is designed.

With the foregoing and other objects in view, which will appear as the description proceeds, the invention consists, in certain novel features of construction, arrangement and combination of parts, hereinafter more fully described and illustrated in the accompanying drawing and particularly pointed out in the appended claim, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which when considered in connection with the following description, my invention, its mode of construction, assembly and operation and many of its advantages, should be readily understood and appreciated.

Referring to the drawing, in which the same characters of reference are employed to indicate corresponding or similar parts through the several figures of the drawing:

Figure 1 is a view in side elevation of a lamp of the "bridge type" embodying the principles of my invention;

Figure 2 is a transverse sectional view through the arm of the lamp;

Figure 3 is a sectional view taken on line 3—3 of Figure 2; and

Figure 4 is a wiring diagram for the lamp.

Stated generally, the invention comprehends the idea of so mounting the switch by means of which the passage of electricity to the lamp is controlled, as to put it in position where it will not interfere with the disposition of the shade

and where it will form and be a part of the transverse arm or part of the lamp stand, with the result that the attractive appearance of the lamp will be greatly enhanced.

5 Referring to the drawing more specifically by characters of reference, the numeral 1 designates a lamp base upon which is mounted the vertical stem 2 adjacent the upper end of which is provided the transverse arm 3, said arm extending 10 from the stem 2 so as to be in position to throw a light onto a table, such as for example, a bridge table or the like. The stem 2 is of a hollow construction and is adapted to receive therethrough the current supply conductors 4 which are 15 threaded through said hollow stem. On the forward end of the arm 3 is provided a suitable lamp socket 5 within which is received the light bulb 30 and to which may also be attached a suitable lamp shade 6 in position to completely surround said light bulb. The socket 5 is of the "keyless" type, the control of the passage of electricity being through my improved switch mechanism, which will now be more specifically described.

20 The transverse arm 3 is also of the hollow type and has threaded therethrough the current supply conductors or wires 7 and 8 and the branch wire 9. The improved circuit closing means illustrated in the drawing comprises a member 30, one end of which is threaded as shown at 11 to the free end of the arm 3, and the other end of said hollow member having threaded therein a suitable rotatable switch generally designated by the reference character 12.

25 As shown in the drawing, my improved switch comprises a body portion 13 of suitable insulating material, through the center of which is disposed a rotatable stem 14, the outer end of which has rigidly secured thereto an actuating knob 15, by means of which said stem 14 may be rotated. To the opposite end of the stem 14 is secured a conducting plate 16 by means of a screw 17 which extends through said plate and is threaded into the free end of said stem 14. The wires 7 and 9 are connected by means of the screws 18 and 19 respectively, to contact plates 20 and 21 respectively, the opposite ends of which plates are rigidly secured by means of the screws 22 to the body portion 13 of the switch mechanism. The plate member 16 is adapted to span the distance between the plate members 20 and 21 and when in that position will complete the circuit to the lamp, and when in a position at right angles thereto will break the circuit to said lamp. The plate member 16 is sufficiently flexible as to remain by reason of its resiliency in any position that it may be moved to by the actuation of the knob 15.

30 From the above it will be apparent that I

have provided a novel and improved switch mechanism for controlling the passage of electricity to the light bulb, said switch being disposed on a portion of the arm of the lamp so as to present the appearance of being a part of said arm. It will also be noted that the elimination of the pull chain at the socket not only enhances the attractiveness of the lamp, but also facilitates the actuation of the switch mechanism as well as facilitating the attachment of the shade to the lamp. Also the use of a "keyless" socket makes for a more economical construction as well as enhancing the attractive appearance of the socket.

35 It will be noted that although in the embodiment illustrated the switch mechanism is disposed adjacent one end of the transverse arm 3, it is to be understood that I do not limit myself to that position as my improved switch mechanism may be disposed at any point along said arm 20 3 or at any point along the hollow stem 2. The disposition of the switch mechanism will at all times be at such a point where it will work in harmony with the general design of the entire lamp. Thus the switch mechanism may form the extreme upper tip of the hollow stem 2, or the same may be disposed at the juncture between the stem and the arm 3 so as to present the appearance of the desired ornamentation at that point of juncture.

40 It is believed that my invention, its mode of construction and assembly and operation, and many of its advantages should be readily understood from the foregoing without further description, and it should also be manifest that while a preferred embodiment of the invention has been shown and described for illustrative purposes, the structural details are, nevertheless capable of wide variation within the purview of my invention as defined within the appended claim.

45 What I claim and desire to secure by Letters Patent of the United States is:

A lamp of the character described having a hollow stand, a transverse arm associated with said stand adjacent the upper end thereof, said arm being of a hollow construction and having a lamp socket disposed at one end thereof, electricity conducting wires extending through said stem and arm for supplying electric energy to a lamp disposed within said socket, a member 50 threaded on the opposite end of said transverse arm and having a rotatable switch disposed therefor controlling the circuit to said lamp socket, said switch including a make and break member mounted for rotatable movement within a 55 plug, said plug being threaded within said last mentioned member to be fixedly secured thereto.

CHAUNCEY E. WALTMAN.
